US0D1004495S

(12) **United States Design Patent** (10) **Patent No.:** **US D1,004,495 S**
(45) **Date of Patent:** **** Nov. 14, 2023**

(54) **FRONT LOWER BUMPER**

(71) Applicants: **Zhejiang Geely Holding Group CO. LTD.**, Hangzhou (CN); **Shanghai Geely Diran Automobile Design CO. LTD**, Shanghai (CN)

(72) Inventors: **Bin Xi**, Shanghai (CN); **Jamie Liam Barrett**, Shanghai (CN); **Tianwei Pan**, Shanghai (CN); **Ning Huang**, Shanghai (CN); **Guy Donovan Burgoyne**, Shanghai (CN); **Peter Horbury**, Shanghai (CN)

(73) Assignees: **Zhejiang Geely Holding Group CO. LTD.**, Hangzhou (CN); **Shanghai Geely Diran Automobile Design CO. LTD**, Shanghai (CN)

(**) Term: **15 Years**

(21) Appl. No.: **29/812,733**

(22) Filed: **Oct. 24, 2021**

(30) **Foreign Application Priority Data**

Aug. 4, 2021 (CN) 202130501022.7

(57) **CLAIM**

The ornamental design for a front lower bumper, as shown and described.

DESCRIPTION

FIG. 1 is a front elevational view of a front lower bumper showing our new design.

FIG. 2 is a rear elevational view thereof.

FIG. 3 is a left side view thereof.

FIG. 4 is a right side view thereof.

FIG. 5 is a top view thereof.

FIG. 6 is a bottom view thereof.

FIG. 7 is a perspective view thereof; and,

FIG. 8 is an another perspective view thereof.

1 Claim, 4 Drawing Sheets
